UNITED STATES PATENT OFFICE.

CHARLES E. ARCHBALD, OF NEW BRUNSWICK, NEW JERSEY.

MACHINE FOR INKING RIBBONS.

1,207,263.

Specification of Letters Patent.

Patented Dec. 5, 1916.

Application filed March 25, 1916. Serial No. 86,671.

To all whom it may concern:

Be it known that I, CHARLES E. ARCHBALD, a citizen of the Dominion of Canada, and residing at New Brunswick, in the 5 county of Middlesex and State of New Jersey, have invented certain new and useful Improvements in Machines for Inking Ribbons; and I do hereby declare the following to be a full, clear, and exact description of 10 the same, reference being had to the accompanying drawings, forming a part of this specification and to the reference numerals marked thereon.

My invention relates to a machine for 15 inking ribbons and is particularly adapted for impregnating or saturating multi-color ribbons for typewriters.

One of the objects of the invention is to 20 provide means for thoroughly and uniformly applying inking materials of different colors upon opposite sides of a ribbon in such a way that the colors will not run or mix, although they are applied immediately adjacent each other upon the ribbon.

25 A further object of the invention is to provide means whereby various widths and thicknesses of ribbon material may be successfully run through the machine and impregnated or coated with a plurality of colors upon adjacent surfaces of the ribbon fabric.

Another object of the invention is to provide means for preventing the flow of the 30 inking material of one color into that of the other while the ribbon is being saturated.

To these and other ends the invention 35 consists in certain improvements and combinations of parts all as will be hereinafter more fully described, the novel features being pointed out in the claims at the end of the specification.

In the drawings, Figure 1 is a top plan 40 view of a machine embodying one form of my invention; Fig. 2 is a side elevation of 45 the machine; Fig. 3 is a sectional view taken on line *a—a* of Fig. 2; Fig. 4 is a sectional view taken on line *b—b* of Fig. 1; Fig. 5 is an enlarged detail sectional view taken longitudinally of the ribbon supporting shaft 50 shown in Fig. 3; Fig. 6 is a sectional view taken on line *c—c* of Fig. 1; Fig. 7 is an elevational view illustrating the support for the supply roll of ribbon and the adjustable means connected therewith for taking care 55 of ribbons of different widths adapted to be run through the machine; Fig. 8 is a sec-

tional elevation taken on line *d—d* of Fig. 1, and Fig. 9 is an enlarged detail sectional view through one of the adjusting screws shown in Fig. 8 for regulating the height of 60 the partition dividing the lower roller into separate inking mediums.

Similar reference numerals throughout the several views indicate the same parts.

Referring more particularly to the drawings, 1 represents the base or bed of the machine which is supported by standards 2. Mounted upon the bed 1 at each side thereof are frames 3 slotted at 4 to receive the upper and lower roller supporting bearings 5 and 6 respectively as clearly shown in Fig. 4. Journaled in the bearings 5 are the reduced ends 7 and 8 of the shaft 9 which carries the top roller 10. The bearings 5 are held against upward displacement by means of 70 cross bars 11 secured by bolts 12 and adapted to close the upper ends of the slotted frames 3 as shown in Fig. 8. In the bearings 6 are journaled the reduced ends 13 and 14 of the shaft 15 which carries the 75 lower roller 16 which comprises the spaced sections 17 and 18, the latter being shown preferably integral with the shaft 15 while the former is adapted to be positioned thereupon and held against turning by a key 19. 80 Screwed upon the threaded portion 19 of the shaft is a locking nut 20 for holding the section 17 against longitudinal movement. The roller sections 17 and 18 are provided with annular grooves 21 and 22 respectively 85 on their inner faces which are adapted to receive the rings or washers of felt or other yieldable material 23 as shown in Fig. 4. Between the sections 17 and 18 of the lower roller and the felt washers 23 is placed a 90 partition 24, the purpose of which will be 95 hereinafter explained.

Mounted upon one corner of the bed of the machine is an upright support 25 secured to the bed by suitable bolts 26. Upon 100 the frame 3 nearest to the support 25 is bolted or otherwise secured an arm 260 in which is journaled at 27 one end of a shaft 28, the opposite end of which is journaled in the top of the support 25. Secured upon 105 the shaft 28 is a gear 29 adapted to mesh with a gear 30 on the end 7 of the shaft 9 which carries the upper roller 10 and also a fly wheel 31. The gear 30 also meshes with a gear 32 on the end 13 of the shaft 15 110 which carries the lower roller 16. The shaft 28 is provided with an idler 33 and a pulley

34 adapted to be driven by a belt, (not shown) for operating the gear 29 to actuate the gears 30 and 32 for driving the rollers 10 and 16 respectively. A belt shifter 34^a is slidably mounted in a bearing 35 on the arm 26 for shifting the belt upon the pulley and the idler. On the outer end of the arm 26 is a bearing 36 in which is journaled a shaft 37 carrying a pulley 38 upon which a belt 39 is mounted, the belt being driven preferably by a pulley 40 mounted upon the shaft 28. The shaft 37 carries a spool 41 upon which the ribbon 42 is adapted to be wound as it is fed between the rollers 10 and 16 from the supply roll 43, which is rotatably mounted upon a removable pin 44 carried by the upright supports 45 slidably mounted on a shaft 46 supported by suitable brackets 47 seated on the bed or base 1. In order that supply rolls of different widths may be used to carry various widths of ribbon material the supports 45 are slidably and adjustably mounted upon the shaft 46, the lower ends 48 and 49 of the supports each having threaded engagement with oppositely threaded portions 50 and 51 respectively of a shaft 52 rotatably mounted upon the brackets 47, one end in a bearing 53 and the other in a sleeve 54 slidably mounted in a bearing on the opposite bracket 47 as shown in Fig. 7. A hand wheel 55 is provided for rotating the shaft 52 to cause the oppositely threaded portions 50 and 51 of the shaft 35 to move the supports 45 either toward or away from each other as may be desired according to the width of the supply roll 43. As the ribbon 42 is adapted upon leaving the roll 43 to pass behind and engage the rotatably mounted shaft 46, guides for the ribbon at this point, are provided in the form of circular projections 56 extending inwardly of the supports 45 as shown in Fig. 7. The end of the shaft 52 opposite the hand wheel 55 is rotatably mounted in the sleeve 54 and extends therefrom into rotatable engagement with an arm 57 and is provided with a groove 58 into which projects one end of a screw 59 seated in the arm 57 whereby the arm 57 is secured in rotatable engagement with the shaft 52. The lower end of the arm 57 carries a hand wheel 60 having an extension 61 in threaded engagement with one of the brackets 47, a collar 62 being mounted upon the extension to maintain the latter in proper position upon the arm. By turning the hand wheel 60 the shaft 52 and the supports 45 thereon may be moved bodily in either direction to properly align or adjust the ribbon carrying supply roll 43 with respect to the partition 24 mounted between the sections 17 and 18 of the roller 16. A somewhat similar ribbon adjusting means is mounted immediately in front of the rollers 10 and 16 which com-

prises a pair of arms 63 extending forwardly from and secured upon the upper ends of the frames 3, as shown in Fig. 1. The arms 63 are adapted to rotatably support a shaft 64 one end of which is threaded to receive a thumb nut 65 rotatably mounted and secured in the forward end of one of the arms 63 and adapted to be turned to move the shaft 64 transversely of the machine to properly align or adjust the ribbon 42 with respect to the partition 24 and the rollers 10 and 16. The shaft at the end opposite to that which receives the thumb nut 65 is reduced as shown at 66 in Fig. 5 and is provided at this point with a sleeve 67 tightly driven upon the reduced portion and adapted to slide therewith in the arm 63 opposite the thumb nut 65 when the shaft 64 is moved in opposite directions by the thumb nut. The sleeve 67 is split or slotted at 68 and a stud 69 carried by the arm 63 engages the sleeve within the slotted portion 68 to prevent the turning of the shaft 64. In order to provide means for receiving and guiding ribbons of various widths upon the shaft 64, I provide right and left hand threads upon opposite sides of the central portion of the shaft and in engagement with these portions are correspondingly threaded thumb nuts 70 carrying reduced shanks 71 rotatably mounted and secured in sleeves 72 which carry guides 73 through the inner ends of which is loosely mounted a small roller 74 journaled in the arms 63 carried by the frames 3. By turning the thumb nuts 70 the guides 73 may either be moved toward or away from each other to accommodate ribbons of different widths, the guides being free to slide upon the roller 74. The spool 41 on the shaft 37 is slidably mounted thereon and may be moved to line up with the guides 73 and supply roll 43 when they have been properly adjusted with respect to the partition 24 and rollers 10 and 16. In placing the ribbon in position upon the machine to be saturated or impregnated with the inking or other material the ribbon supply roll 43 is positioned between the supports 45 upon the pin 44, the free end of the ribbon being carried over the shaft 64 between the guides 73 and over the roller 74 down in front of and between the rollers 10 and 16 and thence to the spool 41 to which it is secured and upon which it is wound when the machine is set in operation by shifting the belt from the idler to the driving pulley 34. Beneath the roller 16 is movably mounted a divided pan or tray 75 adapted in the present instance to hold inking materials of two colors, the tray being divided by the adjustable partition 24, upon opposite sides of which the roller sections 17 and 18 revolve with their lower edges projecting into the inking material

and which are adapted when rotating to carry the ink to the ribbon which is being fed forwardly between the rollers and wound on the receiving spool at the rear of the machine. The pan or tray is supported preferably by a pair of rectangular cross bars 76 which extend through openings in the lower ends 77 of a pair of side plates 78 flanged outwardly at 79 and secured to the bottom of the bearings 6 by suitable screws 80. The pan 75 is provided with side extension plates 75^a which engage the side plates 78 and prevent the transverse displacement of the pan. The side plates 78 are provided with upwardly extending front and back arms 81 and 82 respectively, which are adapted to support cross bars 83 and 84 which have their ends secured to the arms 81 and 82 preferably by means of the screws 85. The pan 75 is provided longitudinally thereof with a grooved bar 86 extending along the bottom and up the end walls of the pan as shown in Figs. 4 and 8. The grooved bar 86 may be either cast integral with or otherwise secured in the pan. The partition 24 is adapted to fit snugly in the groove of the bar to prevent the mixing of the inking material in the opposite sides of the pan. The partition 24 is made adjustable up and down in the groove by means of screws 87 secured to the partition at 88 and extending through thumb nuts 89 having reduced portions 90 extending through and rotatably mounted in the cross bars 83 and 84 as shown in Figs. 8 and 9. The thumb nuts are held against displacement by means of nuts 91 which are riveted upon the extension 90 at the bottom side of the cross bars 83 and 84. The partition 24 is thus made adjustable vertically with respect to the roller 10 and pan 75 so that the distance between the top of the partition and the underside of the roller 10 may be delicately adjusted to suit the different thicknesses of ribbon material that may be run through the machine and at the same time exert sufficient pressure upon the ribbon on both sides of the axis of the rolls to prevent the flow of the ink from one side of the ribbon to the other as the sections of the lower roller carry the ink to the ribbon. The partition 24 is carried upwardly a considerable distance in front of the roller 10 as indicated at 92 and also slightly above the bottom of said roller in rear thereof as indicated at 93 in Fig. 8. This is done to overcome any tendency of the ink to flow or spread across from one of the bottom roller sections to the other at this point, as might be caused by capillary attraction or otherwise. The front portion 92 of the partition is carried up higher on the roller 10 than the rear portion 93 and is intended also to prevent any splashing of the liquid across from one of the lower roller sections to the other which might be caused by the tendency of the revolving roller to throw the ink upwardly on this side of the machine. The portion 93 is carried up in contact with the ribbon approximately to the point where the ribbon begins to leave the lower surface of the roller 10 which is high enough to prevent any of the ink upon opposite sides of the partition from spreading or flowing across from one of the roller sections to the other at this point. The partition 24 is of very narrow width and is preferably adjusted vertically with respect to the top of the lower roller sections to such a degree as to extend thereabove a very limited amount whereby a slightly greater pressure is exerted upon the ribbon between the partition and the upper roller than between the upper and inking roller. The result is that the ribbon upon leaving the rollers is thoroughly and uniformly saturated or impregnated with the two colors upon opposite sides of its center, the inking material being prevented by the partition from mixing upon the ribbon. By reason of the adjustability of the roller section 17 the colors may be applied so close together that no uninked space will be visible between them, or if desired, said roller sections may be adjusted to space the colors apart sufficiently to produce a visible uninked space between them.

The bearings 5 of the upper roller 10 are preferably secured at the top of the frame members 3 by screws 94 extending through the cross bars 11 into the bearings. The lower bearings 6 upon which the pan or tray 75 is suspended are movable up and down in the slotted frames and are supported by rods 95 slidably mounted in the frames as shown in Fig. 4. The rods are threaded on their lower ends at 96 to extend through the short arm 97 of a lever pivoted at 98 to a bracket 99 secured to the bottom of the base or bed 1. The other arm 100 of the lever is provided with an extension 101 having a series of notches 102 which are adapted to receive the looped end of a rod 103 carrying a weight 104 which serves to force the lower roller 16 in position to compress and hold the ribbon 42 in contact with the upper roller 10. The weight 104 may be adjusted upon the lever arm 101 to secure any pressure between the upper and lower rollers which may be found desirable, the shaft 15 at the same time being supported in parallelism to the shaft 9. The rod 95 may also be adjusted upon the lever arm 97 by loosening the jam nut 105 and turning the handle 106 on the bottom of the rod.

Pivoted upon clamping screws 107 on the cross bar 84 are plates 108 which carry at their forward ends vertically disposed scrapers or guards 109 adapted to be positioned upon the end faces of the upper

and lower rollers at their forward sides as shown in Figs. 1 and 6. The scrapers serve to keep the ends of the rollers clean by preventing the accumulation of ink thereon.

5 Pivots mounted upon the arm 26 at 110 is a short arm 111 carrying a grooved pulley 112 for regulating the tension of the belt 39, the arm 111 being adjustably secured upon its pivot by means of a set screw 113 as 10 shown in Fig. 2.

While I have shown one embodiment of my invention I do not wish to be limited to the detail construction of this mechanism as the same may be readily modified without 15 departing from the spirit of my invention, nor do I wish to limit myself to the use of the machine for applying compounds of only two colors to fabric material or to the use of inking typewriter ribbons, as it will be understood that the machine is adaptable for 20 use in connection with other classes of work.

I claim as my invention:

1. In a ribbon inking machine, the combination with a tray for holding inking materials of a plurality of colors, a pair of upper and lower rollers the latter of which is divided and adapted to rotate within the tray and to supply inking material to adjacent surfaces of a ribbon adapted to be fed 25 between the pair of rollers, means for operating the rollers, and a dividing partition extending from the tray upwardly between the parts of the lower roller to their point of contact with the ribbon to prevent the mixing 30 of the inking materials upon said adjacent surfaces of the ribbon.

2. In a ribbon inking machine, the combination with means for holding a plurality of separated inking materials, of a pair of 40 coöperating rollers between which a ribbon is adapted to move, one of the rollers comprising separated contiguous portions arranged to receive the separate inking materials carried by said holding means and to 45 discharge the same upon contiguous adjacent surfaces of the ribbon, means for actuating the rollers, and means operating between the portions of the divided roller for preventing the mixing of the inking materials 50 at the adjoining edges of said surfaces where they contact with the ribbon.

3. In a ribbon inking machine, the combination with means for holding a plurality of separated inking materials, of coöperating 55 rollers between which a ribbon is adapted to move, one of the rollers being arranged to receive the separated inking materials carried by said holding means and to discharge the same upon adjacent surfaces of the ribbon, means dividing the surface of the inking roller at its point of contact with the ribbon to prevent the mixing of the inking materials 60 at the adjoining edges of said surfaces of the ribbon and means for actuating the rollers.

4. In a ribbon inking machine, the combination with means for holding a plurality of separated inking materials, of coöperating rollers between which a ribbon is adapted to be moved, one of the rollers being arranged to receive the inking materials carried by 70 said holding means and to discharge the same upon adjacent surfaces of the ribbon, means operating on the ribbon between the inked surfaces thereon to press it against the non-inking roller.

5. In a ribbon inking machine, the combination with means for holding a plurality of separated inking materials, of coöperating rollers between which a ribbon is adapted to be moved, one of the rollers being arranged to receive the inking materials carried by 80 said holding means and to discharge the same upon adjacent surfaces of the ribbon, adjustable means engaging the ribbon on a line coinciding with the adjoining edges of the inking material applied to the ribbon and pressing it against the non-inking roller, and means for actuating the rollers.

6. In a ribbon inking machine, the combination with means for holding a plurality of separated inking materials, of coöperating rollers between which a ribbon is adapted to be moved, one of the rollers being adapted to receive the inking materials carried by 90 said holding means and to discharge the same upon adjacent surfaces of the ribbon, a partition dividing said last mentioned roller having a portion arranged contiguous to the non-inking roller and having a portion of its 95 edge concentric with the surface of said roller and serving to prevent the mixing of the inking materials applied to the ribbon by the inking roller, and means for actuating the rollers.

7. In a ribbon inking machine, the combination with a pair of rollers, of a tray for holding inking material having a partition therein adapted to divide the tray into separate inking compartments and to separate 110 one of the rollers into sections rotating in said compartments upon opposite sides of the partition and to discharge ink upon adjoining surfaces of a ribbon arranged to be moved between the rollers upon opposite 115 sides of said partition, the edge of the partition lying at the point of contact of the inking roller on the ribbon and serving to prevent the mixing of the inking materials upon said adjoining surfaces and means for 120 actuating the rollers.

8. In a ribbon inking machine, the combination with a pair of rollers, of a tray for holding inking material having a partition therein adapted to divide the tray 125 into separate inking compartments and to separate one of the rollers into sections adapted to rotate in said compartments upon opposite sides of said partition, the partition serving to prevent the mixing of the 130

inking materials upon said adjoining surfaces, means for adjusting the partition relatively to the ribbon and means for actuating the rollers.

- 5 9. In an inking machine the combination with an upper pressing roll and a lower inking roll coöperating therewith, and ribbon supply and rewinding arbors located at opposite sides of said rolls, of guiding devices for the ribbon located in front of the rolls and positioned to direct the ribbon downwardly against the periphery of the pressing roll at a point removed from the point of contact of the inking roll, said 10 15 guiding devices comprising a support over which the ribbon passes and members thereon engaging opposite sides of the ribbon which are adjustable laterally to shift the ribbon.
- 20 10. In an inking machine the combination with an upper pressing roll and a lower inking roll coöperating therewith, and ribbon supply and rewinding arbors located at opposite sides of said rolls, of guiding devices adjustable laterally in front of the rolls and positioned to direct a ribbon downwardly against the upper roll and a device having an edge concentric with the upper roll and adapted to engage a ribbon thereon 25 30 in front of the point of contact with the ink roll.

11. In an inking machine the combination with a frame, upper and lower rolls mounted therein, and ribbon supply and rewinding arbors at opposite sides of said rolls, of a guide rod on the frame located above and in front of the upper roll, a longitudinally movable threaded guide rod on the frame located in front of the first mentioned rod, guide members supported by both rods and adjusting nuts on the threaded rod for moving said members relatively to each other.

12. In combination, a ribbon guide for inking machines comprising two parallel rods one of which is threaded, two spaced guide fingers supported on said rods and nuts on the threaded rod, one carrying each of said fingers, for adjusting said fingers relatively to each other and longitudinally of said rods, a pair of coöperating rollers between which the ribbon passes after leaving the guide and means for supplying inking material to one of the rollers.

13. In a ribbon inking machine, the combination with a pair of rollers one of which is divided and movable bodily with respect to the other, of an ink holding tray connected to and movable with said bodily movable roller, and supplying ink thereto, a partition independent of the tray extending therefrom between the portions of the di-

vided roller, means for guiding a ribbon between said rollers, means for supporting the movably mounted roller in position to hold the ribbon in contact with the other roller and means for rotating said rollers.

14. A ribbon inking machine comprising upper and lower rolls, the latter being formed of adjacently mounted sections provided with grooves upon their inner faces, washers positioned in said grooves, a partition between said washers, means for adjusting the partition transversely of the rolls, means for supplying ink to the lower roll and means for actuating said rolls.

15. A ribbon inking machine comprising upper and lower rolls, the latter being formed of adjacently mounted sections, washers positioned upon the inner faces of the sections, a partition between said washers, means for adjusting the partition transversely of the sections, means for supplying ink to the lower roll and means for actuating said rolls.

16. In a ribbon inking machine, the combination with an upper roller, a lower divided roller, movable relatively toward and from the upper roller, and a tray for supplying ink to the lower roll mounted to move therewith, of a partition supported independently of the roller and tray and extending from the latter between the portions of the divided roller.

17. In a ribbon inking machine, the combination with a frame, a pair of rollers journaled thereon one of which is divided and movable relatively to the other and an ink tray adjustable with the movable roller, of a partition supported on the frame independently of said movable parts and extending from the tray between the parts of the movable roller.

18. In a ribbon inking machine, the combination with an upper roller, a lower divided roller movable toward and from the upper roller, of a partition located between the portions of the lower roller and means for adjusting the partition relatively to the upper roller and supporting it independently of the lower roller.

19. In a ribbon inking machine, the combination with a frame, an upper roller journaled thereon and a lower two part pressure roller guided for movement toward and from the upper roller, of a partition fitted between the parts of the lower roller and devices for adjustably supporting it on the frame for moving said partition relatively toward and from the upper roller.

CHARLES E. ARCHBALD.
